UNITED STATES PATENT OFFICE.

JOHN OLSEN, OF AMES, IOWA.

AXLE-SPINDLE LUBRICATOR.

1,118,674.

Specification of Letters Patent. Patented Nov. 24, 1914.

Application filed April 23, 1914. Serial No. 833,929.

To all whom it may concern:

Be it known that I, JOHN OLSEN, a citizen of the United States of America, residing at Ames, in the county of Story and State of 5 Iowa, have invented certain new and useful Improvements in Axle-Spindle Lubricators, of which the following is a specification.

My invention relates to improvements in force-feed lubricators for dead axle spindles 10 on which the bearing boxes of vehicle wheels are mounted, and the objects of my improvement are, first, to provide means to normally exclude dirt, dust or sand from every part of the grease container; second, 15 to provide a telltale whereby the quantity of available lubricant in the cup may be estimated at sight or accurately measured without opening up the container; and third, to mount the grease cup in the wheel-retaining 20 nut or axle-nut by an oil-tight connection. These, and other minor objects, herein-after incidentally stated, are attained by the mechanical structure illustrated in the accompanying drawings, in which—

25 Figure 1 is a vertical longitudinal section of the whole device including the box and hub mounted on the spindle of the dead axle and the operating wrench inserted; Fig. 2, a top view with the hub and bearing box 30 removed from the spindle.

In all of which views similar reference numerals refer to like parts.

The ordinary axle-nut as here used is shaped with a longitudinally thickened base 35 1 supplemented by an inwardly disposed bearing boss 2 to supply the requisite length of internally-threaded base to securely seat the nut on the outer shouldered threaded end 3 of the spindle. A polygonal outwardly disposed extension 4, to take the usual setting wrench, is supplemented by the further cylindrical extension 6 to give the required length; the whole extension is shaped to form an outwardly opening, concentric, internally-threaded chamber, to receive and seat the open end of the externally-threaded grease-cup.

The grease cup is of cylindrical form, except the outer exterior polygonal portion 17 50 for engagement by a wrench. It is triply sealed in its seat connection to the axle-nut:—its inwardly disposed mouth end 18 fitted against the base of the nut, its thread- 55

intermedial collar 19 fitted against the outwardly disposed mouth end of the seat chamber. This prevents any possible exudation of the compressed lubricant through the joint connecting the grease cup with the nut. The outwardly disposed bottom or head of 60 the cup has the inwardly standing tube 20, disposed axially in the cup and its bore continued outwardly through the center of the head. And the curved wall of the cup is internally threaded from the mouth to 65 ward the head.

An externally threaded piston 21 is fitted to the internal thread of the cup, to be revolved therein and travel forth and back endwise by turning in the cup. A piston 70 stem 22 extends outwardly from the center of the cupped face of the piston to closely fit revolve and travel endwise in the smooth bore of the inwardly standing tube on the head of the grease cup. An axially disposed 75 rectangular recess 23 in the outer end of the stem, is fitted by the square end 24 of the operating wrench, by which the piston is turned to force the lubricant through the ducts to the bearing surfaces or to retire the 80 piston toward the head of the cup for a new charge of lubricant.

The piston stem and the inwardly standing tube are of such lengths as to interlap at all positions of the piston in the cup, and 85 thereby retain the grease cup always closed against sand or dirt. To give a length of piston stem facilitating the required interlap in the tube, the piston-head is cupped reversely to the grease-cup,—as shown in 90 Fig. 1. The retracting of the outer end of the piston stem from the outer end of the bore of the tube indicates the depletion of and the available quantity of lubricant in 95 the cup. This is accurately gaged by the index mark 25 disposed on the shank of the wrench, to coincide with the outer face of the head of the cup when the piston is turned inwardly to its limit.

I claim:

1. A force feed grease-cup, comprising an internally-threaded cup-shaped container, a tube standing axially in the container on the head thereof and the bore of the tube continued outwardly through said head, a piston-head cupped reversely to the container and peripherally threaded therein, and a piston stem disposed in the cup of the pis- 100 105

ton-head to stand in the bore of the tube and adapted for engagement by means to revolve it.

2. A force feed grease-cup, comprising an internally-threaded cup, an inwardly-standing axial tube on the bottom or head of the cup and having its bore continued outwardly through said bottom or head, a peripherally-threaded piston to engage the in-

ternal thread of the cup, and a piston stem disposed outwardly in said tube and having an angular recess in its outer end.

In testimony whereof I have affixed my signature in presence of two witnesses.

JOHN OLSEN.
